UNITED STATES PATENT OFFICE.

ALEXANDER MORISON, OF SAGINAW, MICHIGAN.

TOW-CLEANER.

SPECIFICATION forming part of Letters Patent No. 644,031, dated February 20, 1900.

Application filed March 9, 1899. Serial No. 708,322. (No model.)

To all whom it may concern:

Be it known that I, ALEXANDER MORISON, a citizen of the United States, residing at Saginaw, county of Saginaw, State of Michigan, have invented a certain new and useful Improvement in Tow-Cleaners; and I declare the following to be a full, clear, and exact description of the invention, such as will enable others skilled in the art to which it pertains to make and use the same, reference being had to the accompanying drawing, which forms a part of this specification.

This invention relates to tow-cleaning machines, and has for its object an improved machine adapted to clean up and render suitable for use the tow or flax fiber that has been partially cleaned by the scutching-machine, the object of the machine being to render suitable for spinning purposes that part of the tow which has heretofore been very largely waste matter. That part of the fiber which is called "tow" consists of the coarser part of the fiber, and generally is of shorter fiber than the finer parts from which it is separated, and it is usually mixed more or less with short woody stem material that has not been taken out either in braking or scutching the flax, and my machine entirely cleans out all remnants of the stems and delivers the tow in a condition entirely suitable for spinning purposes.

The machine consists of a feed-belt on which the tow is packed and over which the tow travels to the end of the belt, where it runs under a spiked holding-cylinder and is carried into the path of a revolving steel brush of peculiar construction. The tow moves forward slowly and is caught by the brushes of a rapidly-revolving brush and the short slivers of stem are entirely torn away from the fiber and dropped, while the fiber after being treated by the scutching action of the brush for a time is itself carried forward and delivered at the tail of the machine.

In the drawing the machine is shown in sectional elevation.

A indicates the frame, and B a revolving brush.

C indicates a feed-belt, and D indicates a spiked holding-roll that lies above the feed-belt and close to the revolving brush B.

E indicates a concave made of slats *ee*, be-

low the brush B and so closely in contact with it that sticks and pieces of stem will not pass freely between the edges of the bars *ee* 55 and the ends of the wire of the brush B.

The brush B is made in sections, each section *b* consisting of a number of flexible steel wires, and these wires are what is known as "flat" wires, and they are arranged with their 60 long diameters longitudinal of the cylinder of the brush, so that their greatest flexibility is utilized. Between successive sections are filler-blocks, arranged to prevent the fiber from gathering and clogging in the brush, 65 and each filler-block *d* is rounded off on its outer corner on that side which is in advance when the brush revolves, so that the wire in front of it can yield freely when it strikes the tow. Normally the blocks are entirely free 70 from the wires of the brush, and the wires of the brush are not thickly set, but are entirely free from one another. Each section of the brush is separated from adjoining sections by a slot *c*, through which there is a 75 constant outflow of air when the rotary brush is in motion, and the outflowing current of air aids in keeping the tow from matting in the brush and also aids in separating the wood from the fiber and driving it through 80 the slats of the concave. The upper part of the brush is covered by a casing A'.

At the tail of the machine is located a cleaning-wheel F, around which are set teeth or spikes *f*. This wheel cleans from the brush 85 any fiber that does not drop before reaching the wheel.

The long yielding bristles of the brush strike the tow with a drawing and combing blow, and should there be knots and tangles in the 90 fiber the bristle will yield instead of breaking and tearing the fiber, and the result is that the fiber is combed or brushed out and cleaned without breaking it and destroying it.

What I claim is—

1. In a tow-cleaner, the combination of a feed-apron and holding-roll, a rotary brush provided with long, flexible brush-bristles arranged in sections, and blocks alternating with the brush-sections and arranged to prevent the tow from entering deeply between the bristles, said blocks being normally free from the brushes and being rounded on the outer advance corner, whereby wires in front 95 100 105

of a block can yield freely, substantially as described.

2. In a tow-cleaner, the combination of a hollow rotary brush provided with long, flexible bristles arranged in sections and having air-outlets from the interior of the brush, and blocks alternating with the brush-sections, arranged to be normally entirely free from the brush-sections and having the outer corner on the advance side rounded off, whereby brush-bristles can yield freely backward, substantially as described.

3. In a tow-cleaning machine, the combination of a grated concave, a rotary hollow brush provided with long, flexible bristles ar-

ranged in sections and with air-passages leading between the brush-sections from the interior of the hollow brush, and blocks alternating with the brush-sections, arranged to prevent the tow from entering deeply between the bristles, said blocks being rounded on their outer advance corner, whereby the bristles are permitted to yield backward, substantially as described.

In testimony whereof I sign this specification in the presence of two witnesses.

ALEXANDER MORISON.
